SAFETY STOP FOR SPINDLES

Gottfried Schöllkopf, Murrhardt, Germany

Application March 20, 1957, Serial No. 647,244

Claims priority, application Germany March 31, 1956

4 Claims. (Cl. 57—132)

2

Should it be desired to remove the spindle 1 after it has been stopped from the bolster 4 in direction of the arrow B, the stop 3, the projection 3a of which is a portion of the operating finger 3b, is then tilted in direction of the arrow C about the horizontally extending tilting axis A—A formed by the edge 3c of the leg 3d, which tilting is effected by finger-tip pressure exerted upon the operating finger 3b in direction of the arrow D. This tilting is made possible by the elongated hole 6 in the leg 3d, the entire stop being non-positively secured by the bolt 8 through the action of the compression spring 5 and held by two gripping surfaces of the pocket 9 in the flange 4a of the bolster 4. The spindle 1 can now be removed in direction of the arrow B, as the shoulder 1b of the whorl 1c can now be moved freely past the projection 3a of the stop 3.

Instead of the compression spring 5 there may be used a rubber spring, or the like, filling the pocket between the spindle rail 7 and the flange 4a such that no fly can collect therein (Fig. 3).

An essential feature of the present invention resides in having the bolt 8 as well as the spring 5, by means of which the stop 3 is suspended on the flange 4a of the bolster 4, arranged in the pocket 9 which is cast or machined in the flange 4a. In contrast to known spring-hook arrangements, the bolt 8 is released of power, as on raising the spindle while removing the cop or other yarn receiver in direction of the arrow B. The power is taken up by the flange 4a by means of the stop 3. In addition, the present invention secures the advantage that the bolt is securely arranged within the pocket. A gap of approximately 0.5 mm. in width is provided between the spinning rail 7 and the head of the bolt 8 so that the bolt after but half a turn would already abut against the spinning rail 7, if it should happen that in the course of time the bolt becomes loose owing to vibration of the spinning frame.

Accidental, self-tilting of the safety stop 3 is even then impossible when the cop or other yarn receiver is pulled off from the spindle with considerable force. On the other hand, tilting at will can readily be effected by applying finger tip pressure in direction of the arrow D upon the upper end of the safety stop 3 which is preferably integral and bent from strip steel. Over and above that the present invention assures perfect return of the safety stop 3 to its operating position when the spindle 1 is slipped again on the spindle blade 1d mounted as part thereof in the bolster 4, after it has been removed therefrom.

A further advantage of the invention resides in the fact that the hook 3a, 3b possesses but a very small surface where fly or lint could collect and therefore can be kept clean easily, as besides this hook the safety stop mechanism has no other parts projecting over the edge of the whorl. This results in the additional advantage that the safety stop mechanism may just as well be located at the front or the rear of the spindle with respect to its location in the spinning frame. When placed on the side facing the operator so as to be operative on the stepped shoulder of the whorl, the hook may be located so low that interference with the belt for driving the whorl is impossible.

It is thought from the foregoing description that the advantages and novel features of the invention will be readily apparent.

It is to be understood that changes may be made in the construction and in the combination and arrangement of the several parts provided that such changes fall within the scope of the appended claims, and while two embodiments of the present invention are disclosed, it is to be understood that these embodiments are given by example only and not in a limiting sense, the scope of

The present invention relates to a safety stop for spindles of textile spinning frames or the like, the general object of the invention being to provide means for securing the spindles in their position in the spinning rail when the cops or other yarn receivers are removed therefrom.

Another object of the invention is to provide a safety stop mechanism which is simple and practical in construction, strong and reliable in use, relatively inexpensive to manufacture, and otherwise well adapted for the purpose for which the same is intended.

It is another object of the present invention to provide a safety stop for spindles of textile spinning frames which comprise a safety stop mechanism which is tiltable against the action of a compression spring about an edge formed by a leg of the stop arranged between the spinning rail and the whorl and by a surface extending in a plane running transversely to the spindle axis.

With these and other objects in view which will become apparent in the following detailed description, the present invention will be clearly understood in connection with the accompanying drawings, in which:

Figure 1 is a part sectional side elevational view of the safety stop mechanism constructed in accordance with the present invention;

Fig. 2 is a sectional view taken along line II—II of Fig. 1; and

Fig. 3 is a fragmentary sectional elevational view of another embodiment of the safety stop mechanism.

In the construction illustrated in the drawing, the spindle 1 is rotatably mounted in the bolster 4 as well as removable in direction of the arrow B. The stop 3 comprising a hook-shaped operating finger 3b, a projection 3a and a leg 3d is the main part of the safety stop mechanism. The whorl 1c of the spinning spindle 1 has a stepped shoulder 1a into the step 2 of which extends the hook-shaped portion 3b with its projection 3a, so that the stop 3 is turnable about a horizontally extending axis A—A (Fig. 2). The stop 3 is tiltable against the action of the compression spring 5 about an edge 3c which is formed by the leg 3d of the stop 3 arranged between the spinning rail 7 and the whorl 1c and by a surface extending in a plane running transversely to the spindle axis. The stop 3 is held by a bolt 8 and guided by two gripping surfaces of a pocket 9 in the flange 4a of the bolster 4 supported on the spinning rail 7, so that the bolt 8 extends through an elongated hole in the leg 3d.

The driving belt 10 drives the spindle 1 which is in known manner rotatably mounted as well as axially removable in direction of the arrow B in the hollow bolster 4 by means of a spindle blade 1d extending into the latter. The projection 3a prevents in the position shown in Fig. 1 accidental removal or raising of the spindle 1 in direction of the arrow B when only the cop or other yarn receiver (not shown) supported on the spindle 1 is not to be raised therefrom in direction of the arrow B, since the shoulder 1b of the whorl 1c abuts the projection 3a of the stop 3, upon raising the spindle 1 slightly from its support on the spinning rail 7.

the present invention being determined by the objects and the claims.

What is claimed is:

1. In a spinning frame or the like, a spinning rail, a spindle unit comprising a spindle blade and whorl having a stepped shoulder at its lower end and a bolster having a flange thereon and mounted therewith on said spinning rail by said spindle blade, further including a yarn receiver secured to the upper portion of said spindle above said whorl, said flange of said bolster defining a pocket, a safety stop mechanism mounted in said pocket and comprising a stop member bent from strip steel and including a hook-shaped portion at its upper end and a horizontal leg portion at its lower end, said leg portion extending into said pocket, and a resilient member disposed in said pocket and retaining said stop member in operative stopping position and permitting said stop member to assume an inclined inoperative position, and said hook-shaped portion of said stop protruding over the stepped shoulder of said whorl so as to secure said spindle in its position and prevent it from raising when said yarn receiver is removed therefrom.

2. In a spinning frame or the like, a spinning rail, a spindle unit comprising a spindle blade and a whorl having a stepped shoulder at its lower end and a bolster having a flange thereon and mounted therewith on said spinning rail by said spindle blade, further including a cop or other yarn receiver removably secured to the upper portion of said spindle above said whorl, said flange of said bolster defining a pocket, a safety stop mechanism mounted in said pocket, and said safety stop mechanism comprising a stop bent from strip steel and having a hook-shaped portion at its upper end and a horizontal leg at its lower end extending into said pocket and an elongated hole in said horizontal leg and a screw-threaded bolt extending through said elongated hole and a resilient member mounted on the shank of said bolt, and said hook-shaped portion of said stop protruding over the stepped shoulder of said whorl so as to secure said spindle in its position and prevent it from raising when said cop or other yarn receiver is removed therefrom.

3. In a spinning frame or the like, a spinning rail, a spindle unit comprising a spindle blade and a whorl having a stepped shoulder at its lower end and a bolster having a flange thereon and mounted therewith on said spinning rail by said spindle blade, further including a cop or other yarn receiver removably secured to the upper portion of said spindle above said whorl, the flange of said bolster defining a pocket having two lateral gripping surfaces on the side adjacent said spindle blade, a safety stop mechanism tiltably mounted in said pocket, and said safety stop mechanism comprising a stop bent from strip steel and having a hook-shaped portion at its

upper end and a horizontal leg at its lower end extending into said pocket and an elongated hole in said horizontal leg and a holding means for non-positively holding said safety stop mechanism extending through said elongated hole and a resilient member retaining said safety stop in said pocket and the latter being tiltable against the action of said resilient member about a tilting axis formed by the outer transverse edge of said horizontal leg and by a surface extending in a plane running transversely to the axis of said spindle when finger-tip pressure is exerted upon the hook-shaped portion of said stop in a manner whereby said stop will be held in its tilted position by the two gripping surfaces of said pocket in the flange of said bolster so as to render it inoperative when it is desired to remove said spindle blade.

4. In a spinning frame or the like, a spinning rail, a spindle unit comprising a spindle blade and a whorl having a stepped shoulder at its lower end and a bolster having a flange thereon and mounted therewith on said spinning rail by said spindle blade, further including a cop or other yarn receiver removably secured to the upper portion of said spindle above said whorl, the flange of said bolster defining a pocket having two lateral gripping surfaces on the side adjacent said spindle blade, a safety stop mechanism tiltably mounted in said pocket, and said safety stop mechanism comprising a stop bent from strip steel and having a hook-shaped portion at its upper end and a horizontal leg at its lower end extending into said pocket and an elongated hole in said horizontal leg, a holding means for non-positively holding said safety stop mechanism extending through said elongated hole, a rubber member of a shape complementary to that of said pocket, and said holding means including a bolt having a shank projecting through said rubber member and being secured to said flange, said safety stop in said pocket being tiltable against the action of said rubber member about a tilting axis formed by the outer transverse edge of said horizontal leg and by a surface extending in a plane running transversely to the axis of said spindle when finger-tip pressure is exerted upon the hook-shaped portion of said stop in a manner whereby said stop will be held in its tilted position by the two gripping surfaces of said pocket in the flange of said bolster so as to render it inoperative when it is desired to remove said spindle from said spindle blade.
